CLAIM

The ornamental design for a slab endgrain milling sled as shown and described.

DESCRIPTION

FIG. 1 is a top, front, left side perspective view of a slab endgrain milling sled in accordance with my design;

FIG. 2 is a bottom, rear, right side perspective view of the slab endgrain milling sled;

FIG. 3 is a front elevation view of the slab endgrain milling sled;

FIG. 4 is a rear elevation view of the slab endgrain milling sled;

FIG. 5 is a right side elevation of the slab endgrain milling sled;

FIG. 6 is a left side elevation of the slab endgrain milling sled;

FIG. 7 is a top plan view of the slab endgrain milling sled; and,

FIG. 8 is a bottom plan view of the slab endgrain milling sled.

The broken lines shown in the drawings represent portions of the slab endgrain milling sled that form no part of the claimed design.

1 Claim, 6 Drawing Sheets
